ADJUSTABLE CLAMP.

1,252,638.

Specification of Letters Patent.

Patented Jan. 8, 1918.

Application filed May 14, 1917. Serial No. 168,390.

To all whom it may concern:

Be it known that I, FRANK X. WIEDEMAN, a citizen of the United States, residing at Hartford, in the county of Hartford and 5 State of Connecticut, have invented a new and useful Improvement in Adjustable Clamps, of which the following is a specification.

This invention relates to those clamps 10 which, while more particularly designed for attaching mirrors, spot-lights, reflectors, shades, and screens, to the frames of wind shields of automobiles, may be used for attaching various appliances to other supports. 15 The object of the invention is to provide a simple, cheap and readily adjustable appliance supporting clamp which is so made that it can be quickly arranged to firmly grip frames or posts of any of the sizes and 20 cross sectional shapes commonly used.

Figure 1 of the accompanying drawings shows a top view of one form of clamp which embodies the invention. Fig. 2 shows a side elevation of the same. Fig. 3 shows 25 an edge elevation. Fig. 4 shows a horizontal section on the plane indicated by the line 4—4 on Fig. 2, looking in the direction indicated by the arrow. Fig. 5 shows a vertical section on the plane indicated by the 30 line 5—5 on Fig. 1, looking in the direction indicated by the arrow. Fig. 6 shows holding jaws for the clamp which are designed to grasp a triangular frame post. Fig. 7 shows holding jaws designed to grasp a 35 square post. Fig. 8 shows the jaws used to grip a channel post. Fig. 9 shows the jaws shaped to hold a U-shaped post. Fig. 10 shows a modified form of the clamp with the jaws illustrated as holding an oval post.

40 In the form of clamp first illustrated there is a plate 1 with perforations 2 and 3 for the attachment of any desired appliance. This plate has a socketed head 4 which is designed to receive the inner end of a removable jaw 5 and its stem 6 and the stud 7 which prevents the jaw from rotating. The outer end of the jaw is shaped to fit and clasp the part to which the device is to be attached.

45 The other member of the clamp illustrated has a plate 9 with a slot 10 and a head 11. This head has a threaded socket for receiving the threaded plug 12, and the inner end of the removable jaw 13, the stem 14 of 50 which jaw extends into a central opening in

the threaded plug. The outer end of the plug is shaped for the application of a wrench and the outer end of this jaw is shaped to correspond with the outer end of the complementary jaw carried by the head 60 on the other plate. The two plates are fastened together by means of a bolt 15 which extends through the slot 10 in one plate into a threaded perforation in the other plate, a washer 16 desirably being placed under the head of the bolt. The plate 1 is provided with teeth 17 and the plate 9 has corresponding teeth 18. These teeth are engaged with the heads the desired distance apart and then when the bolt is tightened in such manner 65 as to hold the plates together they cannot separate or move longitudinally with relation to each other.

The two plates are coarsely adjusted and fastened together with the heads separated 70 the desired distance apart. This, of course, can be varied as desired by loosening the bolt and sliding the plates with relation to each other. Jaws having the required frame gripping configurations in their opposing 75 faces are inserted in the heads and then the jaws are tightly clamped against the frame or post to which the device is to be attached by turning in the threaded plug. The jaws first shown have a configuration for gripping a round frame or post. The jaws shown in Figs. 6, 7, 8, 9 and 10 are shaped to enable them to grip frames or posts of various cross sectional shapes.

In the second form shown the body 20 80 of the clamp is made in one piece, with the two heads 21 and 22 integral therewith. The body has a forked stem 23 to which the mirror, light, reflector, shade, or screen may be clamped. The head 21 is provided with a 85 socket for receiving the non-adjustable jaw 24 and its stem 25, while the head 22 is provided with a socket for receiving the adjustable jaw 26 and also the threaded plug 27 which is used to set this jaw up tightly.

100 These clamps are capable of being used with frames or posts of any common cross-sectional shape and size. All that it is necessary to do is to insert in the heads jaws having a particular configuration necessary 105 to fit the particular style of frame or post to which it is desired to clamp the device. The jaws are very cheap and numerous shapes and sizes can be kept in stock and supplied by anyone according to the use to 110

which the clamp is to be put. The device can by this means be fitted by anyone so as to be tightly clamped to any ordinary structure for firmly supporting the desired appliance.

The invention claimed is;

1. A clamp having a body with two heads, each having a cylindrical socket, the socket in one head being screw threaded, a socketed 10 plug screwed into the threaded socket, a cylindrical gripping jaw fitting in the threaded socket and having a stem fitting the socketed plug, and a cylindrical gripping jaw removably fitting in the socket in the other head.
2. A clamp having a body with two heads, one head having a cylindrical socket and the other head having a cylindrical hole, said socket and hole being in axial alinement, a 20 cylindrical gripping jaw fitting and detachably fixed in said socket in one head, a cylindrical gripping jaw fitting and having axial movement in said hole in the other head, and a threaded plug screwed into said hole 25 against the back of the adjustable jaw for forcing that jaw axially toward the non-adjustable jaw.
3. A clamp having two heads provided with opposing cylindrical sockets and adjustable toward and from each other, a cylindrical gripping jaw detachably fixed in

the socket in one head, a cylindrical gripping jaw movable axially in the socket in the other head, and a plug screwed into the socket back of the head in the movable jaw 35 for forcing that jaw axially in the socket toward the jaw in the socket in the other head.

4. A clamp having a body formed of two plates adjustable flatwise with relation to each other, means for holding the plates together flatwise in adjusted position, a head extending from one edge of each plate, said heads having sockets that open toward each other and that are adjusted toward and 45 from each other by the adjustment of the plates, a gripping jaw removably located in the socket in each head, and a threaded plug in one head for forcing the jaw carried by that head toward the jaw carried by the 50 other head.

5. A clamp having a body formed of two plates, a bolt for securing the plates together, coöperating teeth for preventing the sliding of one plate with relation to the other, a socketed head on each plate, a non-adjustable gripping jaw removably located in one head, an adjustable gripping jaw removably located in the other head, and a screw plug for forcing the adjustable jaw 60 toward the non-adjustable jaw.

FRANK X. WIEDEMAN.
